(57) **CLAIM**

I claim the ornamental design for a behind-the-door folding wall shelf, as shown and described.

DESCRIPTION

FIG. 1 is a front, top, and right side elevation perspective view of the behind-the-door folding wall shelf, shown mounted in place behind a door;

FIG. 2 is a front, top, and right side elevation perspective view of the behind-the-door folding wall shelf, shown folded with the shelves exposed;

FIG. 3 is a front, top, and right side elevation perspective view of the behind-the-door folding wall shelf, shown folded with the outer walls exposed;

FIG. 4 is a side elevation view of the behind-the-door folding wall shelf;

FIG. 5 is a front view of the behind-the-door folding wall shelf;

FIG. 6 is a top view of the behind-the-door folding wall shelf;

FIG. 7 is a side elevation view of the behind-the-door folding wall shelf showing the opposite side shown in FIG. 4;

FIG. 8 is a rear view of the behind-the-door folding wall shelf; and,

FIG. 9 is a bottom view of the behind-the-door folding wall shelf.

The broken lines in FIG. 1 of the drawings show unclaimed environment only and form no part of the claimed design.
